ELECTRICAL SWITCHING APPARATUS

George Semos, New York, N. Y.

Application July 15, 1955, Serial No. 522,227

2 Claims. (Cl. 200—160)

This invention relates to a novel electrical switching apparatus, more particularly a switching apparatus suitable for use as a telegrapher's key in the transmission of code by conventional transmitting means.

Notwithstanding the rapid advances in the communications fields, there has still remained a need to employ telegraphic equipment for the transmission of messages by codes such as the Morse code. The transmission of code messages requires the services of a skilled operator who aside from a thorough knowledge of the code symbols must also possess training in manipulation of the transmitting apparatus. Such apparatus consists broadly speaking of a switch for the making and breaking of a circuit whereby the duration of an electrical impulse is varied to produce a series of intermittent signals, so called dots and dashes. This switch, known as a key, is pivotally mounted for rapid manipulation by an operator. When code communications are employed, it is thus apparent that the services of a skilled operator are necessary. In those situations as for example on board ship or in planes, in life boats or in an emergency where the service of the operator are made unavailable due to accident, illness, or the like, communications are cut off.

It is with the above problems in mind that the present construction has been evolved, a construction providing novel telegrapher's key which requires no particular skill for its operation, and may be manipulated by anyone who can read to produce the requisite code signals.

It is accordingly a primary object of this invention to provide an improved electrical switch construction.

A further object of this invention is to provide an improved electrical switching mechanism particularly adapted for the transmission of telegraphic code signals by conventional transmitting apparatus.

Another object of this invention is to provide a novel telegraphic code key which facilitates the transmission of telegraphic codes.

It is also an object of this invention to provide an improved telegraphic key which may be operated by one not trained in the transmission of code.

A further object of this invention is to provide an improved telegrapher's key which requires no particular operational skills for the proper utilization thereof.

An object of this invention is also to provide a telegrapher's key for use on ship and plane installations whereby the loss of services of a skilled radio operator does not leave the ship or plane without communication.

These and other objects of the invention which will be made most manifest and particularly pointed out in the following disclosure are achieved by provision of a mounting board having preferably four key levers supported thereon and adapted for depression through a fixed path. Two of these key levers are of a simple first class type fulcrumed between the point of application of the force and that of the load. The load end of each of the two key levers engages a cam surface on a spring pressed cam of insulating material mounted to extend

2

from a contact lever pivotally supported on the mounting board adjacent said key lever. The relationship between the key lever and contact lever is such that depression of the key lever through its complete path of travel serves to depress the contact lever for a period of limited duration. At the end of the contact lever an electrical contact point is provided. In the path of motion of the contact point, a terminal element of an electrical circuit is provided. One of the aforementioned two key levers serves to bring one contact point into contact directly with said terminal for a relatively short period of time. A spring is provided on the other terminal whereby the other contact point closes an electrical circuit formed between it and the terminal for a relatively long period of time. The remaining two of the aforementioned four levers are simple first class levers having their load ends spring biased each by a spring of different tensions. Contact points are provided at the ends of the latter levers. Utilization of the levers in a manner heretofore made more apparent will serve to permit anyone to transmit the signals requisite for telegraphic communication.

The specific constructional details and their mode of employment will become more apparent from the following description taken in conjunction with the drawing wherein:

Figure 1 represents a perspective view of the novel telegraphic key board.

Figure 2 is a cross sectional view taken on line 2—2 of Figure 1 illustrating the details of a key employed for transmitting a letter spacing signal.

Figure 3 is a cross sectional view on line 3—3 of Figure 1 illustrating the constructional features of a key adapted for transmitting the dot signals of conventional telegraphic codes.

Figure 4 is a cross sectional view on line 4—4 of Figure 1 illustrating the structural details of a telegraphic key employed for the transmission of dash signals.

Figure 5 is a cross sectional view on line 5—5 of Figure 1 illustrating the details of a key employed for the transmission word space signals.

Figure 6 is a schematic view of a wiring diagram of the telegraphic key board illustrated in Figure 1.

Referring now more particularly to the drawings, like numerals in the various figures will be taken to designate like parts.

The novel telegraphic key apparatus 10 comprises a mounting board 11 preferably in the shape of an enclosed housing provided with apertures 12, 13, 14 and 15 through which key levers extend. Letter space key lever 16 having key 17 on its end extends out of the housing through aperture or slot 12. Dot key lever 18 extends through aperture or slot 13 and is provided at its outwardly extending end with key 19. Dash key lever 20 having key or button 21 at its extremity extends through aperture 14. Word space lever 22 having key or button 23 extends from aperture or slot 15.

The dot-transmitting lever 18 shown in Figure 3 is pivoted intermediate its ends at 24 and carries a pin 25 at its outer end. A spring 26 is attached to the lever 18 and to the casing and tends to press the lever 18 against a stop 27.

A lever 28 is pivoted intermediate its ends at 29 and carries upon one of its ends a slide 30 which may be engaged by the pin 25 of the lever 18. The slide 30 has a curved upper edge and is engaged by a spring 31 which is carried by the lever 28 and which tends to maintain the slide 30 in the position shown in full lines in Figure 3.

The opposite end of the lever 28 is connected with a spring 32 the other end of which is attached to the housing. The spring 32 tends to press the lever 28 against

a stop 33. The same end of the lever 28 carries an electrical contact 34.

In the depressed position of the lever 18, which is shown by broken lines in Figure 3, the contact 34 will engage a contact 35 which is adjustably mounted upon a support 36.

The dash transmitting mechanism shown in Figure 4 is similar to the one just described and includes a pivot 37 carrying the lever 20 which is pressed by a spring 38 against a stop 39. Another lever 40 is pivoted at 41 and carries a slide 42 engaged by a spring 43. The lever 40 is pressed by a spring 44 against a stop 45 and carries an electrical contact 46.

In this device, however, the electrical contact 47 which is adapted to engage the contact 46 when the lever 20 is depressed, has the form of a bent leaf spring which will remain in engagement with the contact 46 for a lengthy time period. The contact 47 is adjustably mounted upon a support 48.

The letter spacing lever 16 shown in Figure 2 is pivoted at 49 and is pressed by a comparatively light tensioned spring 50 against a stop 51. A stop 52 limits the downward movement of the lever 16. In its downward position the lever 16 will strike a bell 53 having a comparatively light tone.

The word spacing device shown in Figure 5 is of substantially the same construction and includes a pivot 54 and two stops 55 and 56 for the lever 22. A spring 57 which has stronger tension than the spring 50, presses the lever 22 against the stop 55. The lever 22 may strike a bell 58 which has a heavier tone than the bell 53.

The operation of the apparatus is as follows:

When an operator desires to send out a dot signal, he pushes down the key 19. Then the lever 18 will swing upon the pivot 24 and will raise the lever 28 due to the engagement of the pin 25 carried by the lever 18 with the lower straight edge of the slide 30. The contact 34 carried by the lever 28 will engage the contact 35 and will also engage a contact 59 (Figure 6), thereby closing an electrical circuit which includes the wires 60 and 61, a source of electrical energy and the standard signalling jack (not shown).

As soon as the pin 25 has moved beyond the position shown by broken lines in Figure 3, it will not engage anymore the slide 30, so that the spring 32 will pull the lever 28 back to the position shown in full lines in Figure 3, thereby interrupting the connection between the contact 34 on the one hand, and the contacts 35, and 59 on the other hand. It is thus apparent that the duration of the electrical impulse is not dependent anymore to any substantial extent upon the skill of the operator.

As soon as the operator releases his pressure upon the key 19, the spring 26 will pull the lever 18 back to its initial position; the pin 25 will ride upon the upper curved edge of the slide 30 and will push the slide 30 to the right (looking in the direction of Figure 3) until the pin 25 reaches the lower edge of the slide 30. Then the spring 31 will push the slide 30 back to its position shown in full lines in Figure 3.

When the operator desires to send a dash signal, he will depress the key 21 with the result that the pin 62 carried by the lever 20 and engaging the slide 42, will swing the lever 40 and will establish a connection between the

electrical contact 46 on the one hand, and the electrical contacts 47 and 63 on the other hand. This will close the electrical circuit containing the wires 60 and 61 (Figure 6) and an impulse will be emitted, however, due to the resiliency of the spring 47, the duration of the electrical connection will be longer and the signal will have the character of a dash signal.

As soon as the engagement between the pin 62 and the slide 42 is interrupted in the course of the upward movement of the pin 62, the spring 44 will pull the lever 40 back to its original position.

As soon as pressure upon the key 21 is released, the spring 38 will pull back the lever 20 and due to the provision of the spring 43 the slide 42 will yield to permit the pin 62 to assume its initial position shown in Figure 4.

When the operator has reached the end of a letter he is instructed to depress the key 17 until the bell 53 rings due to the action of the lever 16. This provides the pause necessary for transmission purposes.

Similarly, when the operator reaches the end of a word, he is told to depress the key 23. Since the spring 57 is stronger than the spring 50, the time period until the bell 58 is rung, will be longer, providing the necessary spacing of the signals.

It is thus apparent that by means of the described apparatus the task of sending wireless and telegraphic messages has been simplified to an extent which makes it possible to use the apparatus by an entirely unskilled person.

The switch 70 is used to short-circuit the negative and positive sides so as to make continuous sound when it is left on the "on" position.

It is further apparent, that the illustrated apparatus has been described by way of illustration and not by way of limitation and that it is subject to many variations and modifications. All such variations and modifications are to be included within the scope of the present invention.

What is claimed is:

1. In a code transmitting switch, a lever, a pivot carrying said lever intermediate its ends, a key upon one end of said lever, a spring connected to the other end of said lever, a stop adapted to engage said other end of said lever, said spring pressing said other end of the lever against said stop, another lever, another pivot carrying said other lever intermediate its ends, a slide movably mounted upon one end of said other lever, another spring engaging said slide, a pin carried by said other end of the first-mentioned lever and adapted to engage said slide, a third spring pressing said other end of the second-mentioned lever against said other stop, a conducting contact carried by said other end of the second-mentioned lever, and a signal-emitting contact adapted to be engaged by the first-mentioned contact while said key is being depressed.

2. A switch in accordance with claim 1, within one of said contacts consists of an elongated resilient member, whereby a comparatively long contact time period is provided.
